UNITED STATES PATENT OFFICE.

GEORGE DWIGHT CLARK, OF PLAINVILLE, CONNECTICUT.

FURNITURE-CASTER.

SPECIFICATION forming part of Letters Patent No. 291,494, dated January 8, 1884.

Application filed March 13, 1883. (No model.)

To all whom it may concern:

Be it known that I, GEORGE D. CLARK, of Plainville, in the county of Hartford and State of Connecticut, have invented certain new and useful Improvements in Casters; and I do hereby declare the following to be a full, clear, and exact description of the invention, such as will enable others skilled in the art to which it pertains to make and use 10 the same.

My invention relates to an improvement in casters, and more particularly to that class thereof known to the trade as "French" casters, the object being to produce a grade of 15 this class of casters which shall embody the merits of the old grades, and at the same time surpass them in strength, durability, and cheapness of production.

With these objects in view my invention 20 consists in the combination, with a pintle encircled by two shoulders which are swaged from it, of a washer interposed between said shoulders, one of which is upset after the washer is put in position.

My invention further consists in certain 25 details of construction and combinations of parts, as will be more fully hereinafter described, and pointed out in the claim.

In the accompanying drawings, Figure 1 is 30 a view in perspective of a caster embodying my invention. Fig. 2 is a view thereof in vertical section. Fig. 3 is a view in perspective of a modification of my improvement, and Fig. 4 is a view in section thereof.

French casters consist, essentially, of a pintle, A, having a washer or bearing, B, secured to it, and of a caster-frame, C, supporting a roller, D, my invention consisting in the 35 peculiar adaptation of the pintle to support 40 the washer, and in the construction of the latter.

Referring to the construction shown in Figs. 1 and 2 of the drawings, the washer B is supported between a heavy shoulder, E, formed 45 upon and encircling the pintle, and a similar but smaller shoulder, F, sufficient space between the two shoulders being left to accommodate it. The said shoulders are swaged from the body of the pintle by any approved

means, the shoulder F being upset after the 50 washer has been put in place. As shown, the shoulder E is located above the shoulder F, and this is the preferred construction; but it is apparent that practically the same results may be obtained by reversing this arrangement. By virtue of this construction, 55 which simply involves the formation of two shoulders by swaging them from the body of the pintle, the skin of the metal, wherein its greatest strength lies, is not removed; hence 60 the strength and durability of the completed article.

The shoulders may be formed by hand, or without manual intervention, in purely automatic machinery, the expense of adapting 65 the pintle to receive the washer being comparatively light in either case. The pintle of the prevailing style of French caster is encircled by a groove, into which the inner edges of a malleable washer are forced by 70 compression. This construction involves the formation of the groove, which is attended by considerable expense. It also requires the employment of malleable metal in the fabrication of the washers. The operation of 75 grooving the pintle is much more expensive than that of swaging the shoulders, and malleable washers cost more than those made from sheet or band metal; hence the comparative cheapness of the improved article. 80

The upper face of the washer B is provided with any desired number of points I, which are made integral with or attached to it. These points enter the wood-work of the furniture to which the casters are applied, and 85 prevent the pintles from turning in the sockets provided for their reception.

The modified pintle shown in Figs. 3 and 4 of the drawings is provided with a shoulder, G, and with a shoulder, H, which is located 90 below it, the washer B being interposed between the two and resting upon the latter. The said shoulders are formed by swaging, and the shoulder G is upset after the washer 95 is put in place. If desired, a small washer, J, may be interposed between the washer B and the caster-frame C.

Having fully described my invention, what

I claim as new, and desire to secure by Letters Patent, is—

In a caster, a pintle having two swaged shoulders and a flat disk washer seated against one shoulder and retained in place by the upset metal of the other shoulder, substantially as set forth.

In testimony whereof I have signed this specification in the presence of two subscribing witnesses.

GEORGE DWIGHT CLARK
